LIFTING JACK

Arthur R. Brush, Hornell, N. Y., assignor of one-half to Marie Freedman, Hornell, N. Y.

Application May 27, 1936, Serial No. 82,135

6 Claims. (Cl. 254—100)

This invention relates generally to improvements in lifting jacks, and more particularly to jacks of that type in which the base and lifting members are extensible in opposite directions with respect to a central operating screw-threaded rod.

The main object of the invention is to provide a quick acting lifting jack of great power, which can be very easily operated, and which can be manufactured in quantities and very cheaply from standard sizes of cold drawn steel tubing.

A further object of the invention is to provide a jack of this character which because of its peculiar construction, can be made very small and of light weight in comparison with other jacks of the same power.

Other objects of the invention will become apparent as the detailed description thereof proceeds.

20 In the drawings:

Figure 1 is a central vertical section through the jack forming the subject matter of this application;

25 Figure 2 is a fragmentary end elevation of part of the jack operating mechanism;

Figure 3 is a horizontal section taken on the line 3—3 of Figure 1;

Figure 4 is a horizontal section taken on the line 4—4 of Figure 1;

30 Figure 5 is a fragmentary central vertical section of parts of the jack shown in Figure 1, but with the parts in a different position; and

Figure 6 is a fragmentary detail, partly in section, illustrating means for operating a pawl which 35 forms a part of the jack.

As shown in the drawings, the invention comprises a base plate 7 having an internally screw-threaded tube 8 extending upwardly from the center thereof. A rod 9 having a cylindrical central body portion is provided with right and left screw-threaded portions 10 and 11. The screw-threads on the lower portion 10 engage correspondingly inclined threads on the tube 8; while the screw-threads on the portion 11 engage the 45 correspondingly inclined screw-threads on an upper tube 12.

A sleeve 13 is mounted to slide snugly on the outer cylindrical surface of the tube 8; and is prevented from rotation about the axis of the tube 50 8 by means of a stud 14 projecting from the lower end of the sleeve 13 into a groove 15 formed lengthwise in the outer surface of the tube 8. An upper sleeve 16 is slidably mounted on the outer cylindrical surface of the upper tube 12; and is 55 rigidly connected to the lower sleeve 13 by yokes

17 and 18 which are welded or otherwise suitably secured to the upper end of sleeve 13 and the lower end of the sleeve 16 to hold the aforesaid ends spaced apart a sufficient distance to accommodate the furcations 19 and 20 of a bifurcated operating lever 21.

The furcations 19 and 20 are provided with registering apertures 22 and 23 which receive the central cylindrical portion of the operating rod 9. Between the furcations 19 and 20 there is also 10 suitably secured to the cylindrical portion of the rod 9, a spur gear 24. The slot formed between the furcations 19 and 20 extends sufficiently beyond the outer periphery of the gear 24 to receive a double acting pawl 25, which is fixed to a pivot 15 rod 26 extending through the furcations 19 and 20 of the lever 21. A handle 27 fixed to the upper end of the pivot rod 26 is adapted to move the pawl 25 in either direction to determine the direction of rotation of the gear 24 and the operating rod 9 to which it is fixed.

A spring 28 (see Figures 1 and 3) has one end secured to the furcation 20, and has its other end secured to the handle 27 at a point intermediate the axis of pivot 26 and the outer end of the handle. This is a snap-over spring of well-known type, designed to hold the handle 27 and the pawl mechanism connected thereto, in proper position to determine the rotation of the gear 24 when the lever 21 is oscillated about the axis of the operating screw.

The upper sleeve 16 is provided at its upper end with a stud 29 slidably seated in a groove 30 formed in the upper screw-threaded tube 12 to prevent relative rotation of the tubes 8 and 12. It will be apparent from the drawings that when the lever 21 is oscillated and the pawl 25 is properly positioned, this oscillation will cause the right and left hand screw-threads of rod 9 to rotate about the axis of said rod. This rotation causes the rod 9 to rise bodily in the tube 8, which acts as a nut for the lower screw-threaded portion of the rod 9. In so rising, the rod 9 carries with it the sleeves 13 and 16, since both sleeves are rigidly connected to each other by the yokes 17 and 18. At the same time, the tube 12 is caused to rise on the upper screw-threaded part 11 of the operating rod 9, since it is held against rotation by the engagement of the stud 29 with the groove 30. The gear 24 during this oscillation of the lever 21, is yieldingly held against rotation by the drag of the pawl by means of a ball 31 seated in a bore 32 formed in the yoke 18 and against the spring 33 positioned in said bore by a machine screw 34.

50 55

The tube 12 at its upper end is recessed to provide a seat for a nut 35, which may be welded or otherwise secured in its seat, engaging screw-threads 36 on a lifting rod 37 manually adjustable relative to the tube 12. The operating rod 9 is bored axially to receive the rod 37 slidably. A cap 38 is fixed to the outer end of the rod 37. The parts are so proportioned that when the rod 37 is screwed out to its limit, part thereof will always remain in the bore of the rod 9 to prevent buckling of the jack when fully extended under heavy loads. In effect, the nut 35 forms an inwardly directed screw-threaded flange at the upper end of the tube 12 to support the manually adjustable rod 37.

As appears in Figures 1, 3, and 4 of the drawings, the lever 21 is provided with a comparatively short handle 39 which may be operated to rotate the gear 24 whenever the object to be lifted is located to permit such operation. However, where the jack must be positioned in some location where it is not convenient to operate the handle 39 directly, there is provided an extension 40 having a socket 41 at one end thereof to fit snugly over the handle 39. The socket 41 and the handle 39 are provided with registering apertures to receive a pin 42 which may be held in convenient position on the extension member 40 by a chain or other flexible member 43.

It will be apparent from the drawings and as previously described, the handle 21 may be moved in one direction or the other to position the pawl 25 for engagement in either direction with the teeth of the gear 24. In order to position this pawl when the extension 40 is used, there is secured to the said extension 40 a tube 44 through which extends slidably, a wire 45 having an operating knob 46 secured to the outer end thereof. The inner end of the wire 45 is bent to engage a bore 47 formed near the outer end of one arm of the pawl 45. By this means, the pawl 25 may be operated in either direction, even when the jack is so positioned that the hands of the operator cannot reach the handle 21. The spring 28 holds the wire 45 in whatever position it may have been moved in locating the pawl 25 against the teeth of gear 24.

It is to be understood that the invention is not to be considered as limited to the specific construction and arrangement described herein, since it is evident that many changes may be made without departing from the scope of the invention as defined by the claims appended hereto.

What I claim is:

1. A jack comprising a base, an internally screw-threaded tube fixed to said base, an operating rod having left and right externally screw-threaded parts extending in opposite directions from the center thereof, one of said parts having its threads engaging the threads in said tube, a second tube internally screw-threaded to receive the screw-threads on the other part, a sleeve slidably on the first named tube, said tube having a groove extending lengthwise of its outer surface, a stud projecting from the lower end of said sleeve into said groove, a sleeve slidably on said second tube, said second tube being provided with a groove extending lengthwise of the outer surface, a stud projecting from the upper end of the second sleeve into the groove on the second tube, means for rigidly connecting said sleeves to each other, said operating rod being bored axially, a lifting rod adjustable on the upper end of said second tube and having part thereof slidable in the bore of said operating rod.

2. A jack comprising a base, an internally screw-threaded tube fixed to said base, an operating rod having left and right externally screw-threaded parts extending in opposite directions from the center thereof, one of said parts having its threads engaging the threads in said tube, a second tube having internal screw-threads engaging the screw-threads on the other of said parts, means for rotating said operating rod about its axis, a sleeve slidably on the first named tube, a second sleeve slidably on the second named tube, means for rigidly connecting said sleeves to each other, cooperating means on said sleeves and tubes to prevent rotation of said operating rod, said operating rod being bored axially, said second tube having a screw-threaded flange extending over the upper end of said operating rod, and a lifting rod slidable in the bore of said operating rod, and having a part thereof in screw-threaded connection with said flange.

3. A jack comprising a base, an internally screw-threaded tube fixed to said base, an operating rod having left and right externally screw-threaded parts extending in opposite directions from the center thereof, one of said parts having its threads engaging the threads in said tube, a second tube internally screw-threaded to receive the screw-threads on the other part, means for rotating said operating rod about its axis, means slidably connected to said tubes to prevent rotation of the upper tube about said axis, said operating rod being axially bored, and a lifting rod slidable in the bore of said operating rod and adjustably connected to the second named tube.

4. A jack comprising a base, an internally screw-threaded tube fixed to said base, an operating rod having left and right externally screw-threaded parts extending in opposite directions from the center thereof, one of said parts having its threads engaging the threads in said tube, a second tube having internal screw-threads engaging the screw-threads on the other of said parts, means for rotating said operating rod about its axis, a sleeve slidably on the second named tube, a second sleeve slidably on the second named tube, means for rigidly connecting said sleeves to each other, cooperating means on said sleeves and tubes to prevent rotation of the second tube about its axis during the rotation of said operating rod, said operating rod being axially bored, and a lifting rod slidable in the bore of said operating rod and adjustably connected to the second named tube.

5. A jack comprising a base, an internally screw-threaded tube fixed to said base, an operating rod having left and right externally screw-threaded parts extending in opposite directions from the center thereof, one of said parts having its threads engaging the threads in said tube, a second tube internally screw-threaded to receive the screw-threads on the other part, a sleeve slidably on the first named tube, said tube having a groove extending lengthwise of its outer surface, a stud projecting from the lower end of said sleeve into said groove, a sleeve slidably on said second tube, said second tube being provided with a groove extending lengthwise of its outer surface, a stud projecting from the upper end of the second sleeve into the groove on the second tube, means for rigidly connecting said sleeves to each other, said operating rod being axially bored, and a lifting rod slidable in the bore of said operating rod.

bore of said operating rod and adjustably connected to the second named tube.

6. A jack comprising a base, an internally screw-threaded tube fixed to said base, an operating rod having left and right externally screw-threaded parts extending in opposite directions from the center thereof, one of said parts having its threads engaging the threads in said tube, a second tube internally screw-threaded to receive the screw-threads on the other part, a gear fixed to the center of said operating rod, a handle

member pivoted to said rod and extending radially from the axis thereof, a pawl pivoted to said handle and adjustable in either direction into engagement with the teeth of said gear to effect rotation thereof in either direction, means for yieldingly holding said pawl in adjusted position, said operating rod being axially bored, and a lifting rod slideable in the bore of said operating rod and adjustably connected to the second named tube.

ARTHUR R. BRUSH.
